UNITED STATES PATENT OFFICE.

GEORGE W. SWIFT, JR., OF BORDENTOWN, NEW JERSEY.

MECHANISM FOR MAKING OPEN-FACE ENVELOPS.

1,337,734.

Specification of Letters Patent. Patented Apr. 20, 1920.

Application filed July 28, 1915. Serial No. 42,250.

To all whom it may concern:

Be it known that I, GEORGE W. SWIFT, Jr., a citizen of the United States, residing at Bordentown, in the State of New Jersey, have invented a certain new and useful Improvement in Mechanism for Making Open-Face Envelops, whereof the following is a specification, reference being had to the accompanying drawings.

10 My invention relates to envelopes of the class wherein the openings in the face thereof, for display of the address, etc., are covered by patches of transparent material sealed thereon to prevent access to the contents of the envelopes through said openings. The mechanism hereinafter described is arranged to apply adhesive material directly upon the transparent material after the latter has been cut or otherwise formed in individual patches, each adapted to cover a single envelop opening; each of said patches being carried, during the gumming operation, by a roll having means holding the patch thereon. As hereinafter described, 15 such holding means includes gripping mechanism which engages the edge of the patch before it is gummed and releases it after its forward edge is caught upon the envelop web by the adhesive carried by the 20 patch.

25 My invention includes the various novel features of construction and arrangement hereinafter more definitely specified and claimed.

30 In the drawings; Figure I is a diagrammatic, vertical, sectional view of rotary mechanism for contemporaneously progressing and punching an envelop web, progressing a web of transparent material, cutting 35 pieces therefrom to form individual patches, providing said patches with adhesive, and applying said adhesive patches in registry with the openings in said envelop web.

40 Fig. II is an elevation of a pair of envelop web punching rolls such as indicated at the left hand side of Fig. I.

45 Fig. III is an elevation of a roll, such as indicated in Fig. I, for making imprints of adhesive on the transparent patches.

50 Fig. IV is a plan view of a web of paper or other suitable flexible fabric from which envelopes may be formed, showing the transparent patches applied thereto, transversely, and an envelop blank severed therefrom.

55 Fig. V is a view similar to Fig. IV but showing the adhesive patches applied to the

envelop web longitudinally, and an envelop blank severed therefrom.

Fig. VI is a rear elevation of an envelop formed from a blank such as shown in 60 Fig. IV.

Fig. VII is a rear elevation of an envelop formed from a blank such as shown in Fig. V.

65 In making envelopes from a continuous web, by the mechanism shown in Fig. I, the primarily imperforate web 1 may be progressed relatively to the punching mechanism comprising the rolls 2 and 3, shown in Figs. I and II, respectively provided with 70 the male die 5 and female die 6, and punched therewith to form successive openings 8 therein as shown in Fig. IV; said openings being in such spaced relation as to appear in respective individual blanks 10, subsequently divided from said web 1, as indicated in Fig. IV. Said web may be conveniently progressed by frictional engagement thereof between the rolls 12 and 13 which are relatively spring pressed toward 75 each other.

80 The patches 14 are formed from the transparent web 15 which is progressed contemporaneously with said web 1, but at a slower rate, by and between the pair of feed rolls 16 and 17 to guides 23, whereby said web is presented in plane form between the shear rolls 18 and 19 which respectively carry cutters 20 and 21 in such co-operative relation as to shear from said web 15 successive 85 patches 14; one such patch being sheared from said web at each revolution of said rolls 18 and 19 in the direction of the arrows shown in Fig. I. Said web 15 is directed from said shear rolls 18 and 19 between the guides 23, to the platen roll 25 which is the same size as rolls 12, and 13, and, therefore, progresses the patch at the same rate as envelop web 1. Roll 25 has a pair of gripper levers 26 carried by the 90 shaft 27 having an arm provided with the roller 28 for co-operation with the stationary cam 29, whereby the outer ends of said grippers are moved toward and away from the circumferential face of said roll 25 to 95 alternately grip the forward edges of the patches thereon and release them. Said shaft 27 may be spring pressed either to engage or to disengage the patch, in opposition to the action of a cam, but, with the 100 cam 29, is spring pressed to disengage the patch. Said shaft 27 is spring pressed to 105 disengage the patch. Each of said patches is thus car-

ried on said platen roll 25 in opposition to the gumming roll 31 which carries the type form 32 adapted to make imprints of adhesive material such as indicated at 34 in 5 Figs. IV and V. Said type form 32 receives a coating of the adhesive material 36 from the transfer roller 37 which is in operative relation with the coating roller 39 which dips into a supply of said adhesive 10 material in the tank 40. The roll 42, extending above the envelop web 1, as shown, presses the latter toward the platen roll 25 so that as the latter turns it presents the patch 14 in position to be caught upon the 15 envelop web by the adhesive carried by the patch and the gripping mechanism aforesaid is arranged to release the patch as soon as its forward edge is thus caught, so that it will be carried forward by the movement 20 of the envelop web and pressed upon the latter between said rolls 25 and 42.

Although the form of my invention shown in Fig. I is adapted to apply the patches 14 upon the envelop web in registry 25 with openings which extend transversely with respect to said web; it is to be understood that similar mechanism may be employed to apply such patches to cover successive openings 45 extending longitudinally in the envelop web 46 as shown in Fig. 30 V, from which individual blanks 47 are subsequently severed as indicated in that figure. The blanks 10 shown in Fig. IV may be folded to form envelopes 48 as shown in Fig. 35 VI, and the blanks 47 shown in Fig. V may be folded to form envelopes 50 as shown in Fig. VII.

Therefore, I do not desire to limit myself to the precise details of construction and 40 arrangement herein set forth, as it is obvious that various modifications may be made therein without departing from the essential features of my invention as defined in the appended claims.

45 I claim:—

1. Mechanism for making open face envelopes, including means arranged to continually progress an envelop web at a uniform rate while forming a series of openings 50 therein; means arranged to continually progress a web of transparent material, means arranged to cut from said transparent web pieces adapted to form respective individual patches to cover the openings in said envelop web, means arranged to provide each of said severed individual patches with an imprint of adhesive material, and means for applying the patches successively to the openings in the envelop web.

60 2. Mechanism for making open face envelopes, including means arranged to continuously progress an envelop web having openings therein; means arranged to continuously progress a web of transparent material; means arranged to cut from said

transparent web pieces adapted to form respective individual patches to cover the openings in said envelop web; means arranged to provide each of said severed individual patches with an imprint of adhesive material; including a gumming roll and a platen roll opposed to said gumming roll; means whereby said platen roll picks up each patch in succession and carries it while it is being gummed, applies it upon said envelop web to cover an opening therein and releases it only after it has been caught at its forward end upon said envelop web by the adhesive on said patch.

3. Mechanism for making open face envelopes, including means arranged to continuously progress an envelop web having openings therein; means arranged to continuously progress a web of transparent material; means arranged to cut from said transparent web pieces adapted to form respective individual patches to cover the openings in said envelop web; means arranged to provide each of said severed individual patches with an imprint of adhesive material; including a gumming roll and a platen roll opposed to said gumming roll, and in engagement with said envelop web, which platen roll picks up each patch in succession and carries it while it is being gummed; and 90 a movable gripper and actuating means arranged to coöperate with said gripper, whereby said gripper is moved to alternatively grip said patch, and release it only after it has been caught at its forward end 100 upon said envelop web by the adhesive on said patch.

4. Mechanism for making open face envelopes, including means arranged to continually progress an envelop web having openings therein; means arranged to continuously progress a web of transparent material; means arranged to cut from said transparent web pieces adapted to form respective individual patches to cover the openings in 110 said envelop web; means arranged to provide each of said severed individual patches with an imprint of adhesive material; including a gumming roll and a platen roll opposed to said gumming roll, and in engagement with said envelop web; means on said platen roll arranged to grip each patch, carry it while it is being gummed and release it only after it has been caught at its forward end upon said envelop web by the 115 adhesive on said patch; and means opposed to said platen roll arranged to press said patches on said envelop web.

5. Mechanism for making open face envelopes, including means arranged to continuously progress an envelop web having openings therein; means arranged to continuously progress a web of transparent material; means arranged to cut from said transparent web pieces adapted to form re- 125 130

- successive individual patches to cover the openings in said envelop web; means arranged to provide each of said severed individual patches with an imprint of adhesive material; including a gumming roll and a platen roll, which platen roll picks up each patch in succession and carries it while it is being gummed; a gripper lever and actuating means arranged to coöperate with said gripper lever, whereby the outer end of said lever is moved toward and away from the circumferential face of said platen roll to alternately grip the edge of a patch and release it; and means opposed to said platen roll arranged to present the envelop web for engagement with the adhesive on said patches, said actuating means being arranged to release each patch only after it has been caught at its forward end upon said web by the adhesive on said patch.
6. Mechanism for making open face envelopes, including means arranged to continuously progress an envelop web having openings therein; means arranged to continuously progress a web of transparent material; means arranged to cut from said transparent web pieces adapted to form respective individual patches to cover the openings in said envelop web; means arranged to provide each of said severed individual patches with an imprint of adhesive material; including a gumming roll and a platen roll opposed to said gumming roll, which platen roll picks up each patch in succession and carries it while it is being gummed; a gripper lever, a spring pressed rock shaft, carrying said gripper lever, an arm on said rock shaft, provided with a roller, a cam arranged to coöperate with said roller, whereby the outer end of said lever is moved toward the circumferential face of said platen roll to grip the edge of the patch, a roll opposed to said platen roll arranged to present the envelop web for engagement with the adhesive on said patches, said cam being so disposed as to release said gripper after each patch has been caught at its forward end upon said envelop web by the adhesive on said patch.
7. In a machine of the character described, the combination of means for moving envelop material having spaced window openings formed therein, means for successively feeding separated strips of transparent material into engagement with the moving envelop material, and gumming mechanism arranged to apply bands of gum to the successive strips of transparent material during their movement toward the envelop material and in position to engage and adhere to the envelop material around the window openings.
8. In a machine of the character described, the combination of means for moving a web of envelop material, means for cutting a succession of spaced window openings therein, means for successively feeding separated strips of transparent material into engagement with the moving web of envelop material, and gumming mechanism arranged to apply bands of gum to the successive strips of transparent material during their movement toward the envelop material and in position to adhere to the web around the window openings.
9. In a machine of the character described, the combination of means for feeding a continuous web of envelop material, means for cutting a succession of spaced window openings therein, means for feeding a continuous web of transparent material and cutting the same into strip lengths, means for successively moving said strip lengths of transparent material into engagement with the moving web of envelop material, and gumming mechanism arranged to apply bands of gum to the successive strip lengths of transparent material during their movement toward the web of envelop material.
10. In a machine of the character described, the combination of means for continuously moving a web of envelop material having spaced window openings formed therein, means for feeding a web of transparent material and cutting the same into separated strips, a cylinder adapted to carry successive strips of transparent material into engagement with the moving web of envelop material and press them thereon, and gumming mechanism arranged to apply successive separated bands of gum to the strips of transparent material during their movement toward the web of envelop material.
11. In a machine of the character described, the combination of means for moving envelop material having spaced window openings formed therein, means for successively feeding separated strips of transparent material into engagement with the moving envelop material, and gumming mechanism arranged to apply bands of gum to the separate strips and in position to engage with and adhere to the envelop material around the window openings.
12. In a machine of the character described, the combination of means for moving a web of envelop material, means for cutting a succession of spaced window openings therein, means for successively feeding separated strips of transparent material into engagement with the moving web of envelop material, and gumming mechanism arranged to apply bands of gum to the successive strips of transparent material in position to adhere to the web around the window openings.
13. In a machine of the character described, the combination of means for feeding a continuous web of envelop material,

means for cutting a succession of spaced window openings therein, means for feeding a continuous web of transparent material and cutting the same into strip lengths, 5 means for successively moving said strip lengths of transparent material into engagement with the moving web of envelop material, so as finally to cover the window openings, and gumming mechanism arranged to apply bands of gum to the successive strip lengths of transparent material subsequent to their separation into strip lengths.

14. In a machine of the character described, the combination of means for continuously moving a web of envelop material having spaced window openings formed

therein, means for feeding a web of transparent material and cutting the same into separated strips, a cylinder adapted to carry 20 successive strips of transparent material into engagement with the moving web of envelop material and press them thereon, and gumming mechanism arranged to apply successive separated bands of gum to the 25 strips of transparent material subsequent to their separation into strip lengths.

In testimony whereof I have hereunto signed my name at Bordentown, New Jersey, this twenty-fourth day of July, 1915.
